UNITED STATES PATENT OFFICE

CHARLES F. ROOT, OF CLEVELAND, OHIO, ASSIGNOR TO THE CHANDLER & PRICE COMPANY, OF CLEVELAND, OHIO, A CORPORATION OF OHIO

SHEET REGISTERING DEVICE

Application filed March 17, 1928. Serial No. 262,503.

The present improvement relates more particularly to devices for registering a sheet of paper on the platen in printing presses of the so-called platen or Gordon type. It will be understood, however, that the invention is not necessarily limited to use in any such particular type of press. Ordinarily two end stops and one side stop are provided on such platen and, preliminarily to printing, the sheet requires to be placed with its corresponding edges in contact with these stops in order that it may properly register with the form. The object of the present invention is to provide a device that is not only adapted thus automatically to shift the sheet as may be necessary, but which is simple and compact in its construction. A further object is to mount the device so that it will not interfere with the raising of the tympan bail, in order to make ready the platen for printing. To the accomplishment of the foregoing and related ends, the invention, then, consists of the means hereinafter fully described and particularly pointed out in the claims, the annexed drawings and the following description setting forth in detail certain mechanism embodying the invention, such disclosed means constituting, however, but one of various mechanical forms in which the principle of the invention may be used.

In said annexed drawings:—

Fig. 1 is a broken plan view of a printing press equipped with my present improved sheet registering device; Fig. 2 is a front elevation thereof; Fig. 3 is an end elevation of the same; Fig. 4 is a part vertical section and part end elevation of one portion of the device, the plane of such section being as indicated on the line 4—4, Fig. 2; and Fig. 5 is a partial front elevation, like that of Fig. 2, but showing a modification in the construction of the device.

In the several figures of the drawings, the device is shown as applied to the platen 1 of a typical Gordon press. It has been deemed unnecessary to illustrate the manner in which such platen is supported for the oscillatory movement which requires to be imparted thereto in order to bring a sheet thereon into contact with the form (not

shown). It has similarly been deemed unnecessary to illustrate the means whereby the gripper bar 2, that is pivotally attached at its respective ends to the lower edge of the platen, is actuated, but it will be understood that incidentally to oscillation of the platen, said bar is likewise oscillated so as to swing the gripper fingers 3 carried thereby downwardly against the face of the platen, their function being to retain the sheet in place during the printing operation. To accommodate said fingers to sheets of various size, they are preferably adjustably mounted on the bar, being secured in desired location by means of clamp nuts 4. The usual two end stops 5 and side stop 6 are diagrammatically shown in Fig. 1, it being understood that these stops will be variously located, depending upon the size of the sheet and other conditions.

Referring more particularly to the form of the device shown in Figs. 1 to 4, inclusive, the device of present interest will be seen to comprise as its principal element an arm 10 that is provided at its outer or free end with resilient sheet-receiving and gripping fingers of familiar construction. As illustrated, there are three such fingers resembling the tines of a fork, the central finger 11 being arranged to extend in close fitting contact with the surface of the platen or rather of the tympan secured thereon, so that a sheet delivered onto the latter may ride over said finger and rest on the upper surface thereof. The two other fingers 12 are curved downwardly and then upwardly so as to be adapted to contact with the upper surface of such sheet with sufficient pressure to cause the sheet to follow the movement of arm 10 until its edges are brought into abutment with stops 5 and 6, as hereinafter described, whereupon the fingers will slide freely off of the sheet.

Arm 10 at its opposite or lower end is longitudinally slotted so as to adapt it to be adjustably secured, by means of a screw 13, in a seat 14 formed in the upper face of a supporting member 35. The latter includes a cylindrical stud 36 rotatably mounted in a suitable bearing therefor provided in a brack-

et 37 that, as best shown in Fig. 2, comprises two parts adapted to be drawn together by means of a screw 38, such two parts being formed with rabbeted grooves that fit a rail 39 of complementary cross-section attached to the lower edge of the platen. As a matter of fact, such rail will be a part of the usual tympan retaining bail with which the platen is ordinarily provided.

Surrounding the lower end of stud 36, which projects through the corresponding bracket part, is a coil spring 40 that is attached at one end to said stud and at the other to the under side of the bracket where-
15 by tendency to rotate in a counter-clockwise direction is normally imparted to the base 35 and arm 10 carried thereby. However, the base includes a lateral projection 41 that is provided with a downwardly directed pin 42 so disposed as to have sliding contact with the adjacent inner edge of the gripper bar 2, as best shown in Figs. 2 and 4. Oscillation of said bar 2, accordingly, will serve to oscillate the base 41 about stud 36 and impart 25 a corresponding swinging movement to arm 10.

Instead of having the pin 42 so arranged as to contact with the adjacent inner edge of the bar 2, it may, as shown in the modified 30 construction of Fig. 5, be arranged to contact with the outer face of said bar. In such case, however, the spring 42 that surrounds stud 36 will be coiled in the opposite direction from that shown in Fig. 2, so as to tend 35 to rotate the base 35 and arm 10 in a clockwise direction.

The foregoing registering device, it will be obvious, may be readily adjusted longitudinally of bar 2 by simply loosening the nut that 40 secures the bracket. All parts of the device, it will be observed, are carried by said bracket, thus rendering the device entirely self-contained. At the same time the parts may 45 be readily disassembled or assembled as occasion may require. Furthermore, the device, being carried wholly by the tympan bail, will not interfere with the raising of the latter in order to make ready.

Other modes of applying the principle 50 of my invention may be employed instead of the one explained, change being made as regards the mechanism herein disclosed, provided the means stated by any of the following claims or the equivalent of such stated 55 means be employed.

I therefore particularly point out and distinctly claim as my invention:—

1. The combination with a platen having an end stop and a side stop thereon, of a gripper bar oscillatorily mounted on the lower 60 edge of said platen, a sheet receiving and carrying device, a support to which said device is pivotally attached, means for regulably securing said support along the lower 65 edge of the platen, and means for oscillating

the sheet receiving and carrying device, said means being unconnected to said gripper bar but being actuated at least in part thereby.

2. The combination with a platen having an end stop and a side stop thereon, of a gripper bar oscillatorily mounted on the lower edge of said platen, a sheet receiving and carrying device, a support-bracket to which 70 said device is pivotally attached, clamping means securing said support bracket along the lower edge of the platen, spring means for oscillating the sheet receiving and carrying device in one direction, and means unconnected to said gripper bar but actuated thereby for oscillating the sheet receiving 75 and carrying device in the other direction.

3. The combination with a platen having an end stop and a side stop thereon, of a gripper bar oscillatorily mounted on the lower edge of said platen, a support-bracket regulable along such platen-edge, a sheet receiving and carrying device pivotally connected to said bracket, means for clamping said support-bracket in regulated position, a member pivoted to said support bracket about an 80 angle at approximately right angles to the axis of said bar, a pin projecting downwardly from said member and adapted to have sliding contact with said bar, and resilient means connected with said member for normally maintaining said pin in contact with 85 said bar.

4. The combination with a platen having an end stop and a side stop thereon, of a gripper bar oscillatorily mounted on the lower edge of said platen, a support-bracket regulable along such platen-edge, means for clamping said support-bracket in selected position, a member having a stud pivotally mounted in said bracket and projecting therethrough, the axis of said stud being at approximately right angles to that of said bar, a pin projecting downwardly from said member in parallel relation to said stud and adapted to have sliding contact with said bar, a coil spring surrounding the projecting portion of said stud connected at one end therewith and at its other end with said bracket, whereby said pin is normally maintained 100 thus in contact with said bar, and a sheet receiving and carrying device attached to said member.

5. The combination with a platen having an end stop and a side stop thereon, of a gripper bar oscillatorily mounted on the lower edge of said platen, a bracket adapted to be secured to such platen-edge in selected position theralong, a supporting member having a stud pivotally mounted in said bracket and projecting therethrough, the axis of said stud being at approximately right angles to that of said bar, a pin projecting downwardly from said member in parallel relation to said stud and adapted to have 105 sliding contact with the inner face of said 110 platen.

bar, a coil spring surrounding the projecting portion of said stud connected at one end therewith and at its other end with said bracket, whereby said member is rotated in a counter-clockwise direction and said pin thus normally maintained in contact with said bar, and a sheet receiving and carrying device attached to said member.

Signed by me, this 14th day of March,
10 1928.

CHARLES F. ROOT.
